CLAIM

The ornamental design for a bar, as shown and described.

DESCRIPTION

FIG. 1 is a front perspective view of the bar of the present invention having a fixed upper bar surface showing my new design;

FIG. 2 is a rear perspective view thereof;

FIG. 3 is a top plan view thereof;

FIG. 4 is a front elevational view thereof;

FIG. 5 is a bottom plan view thereof;

FIG. 6 is a left side view thereof;

FIG. 7 is a right side view thereof; and,

FIG. 8 is a rear elevational view thereof.

The dotted lines shown in the figures do not form a part of the claimed design.

1 Claim, 3 Drawing Sheets(56)
